UNITED STATES PATENT OFFICE.

FRANK VITTNER, OF CHICAGO, ILLINOIS.

WINDOW.

SPECIFICATION forming part of Letters Patent No. 602,885, dated April 26, 1898.

Application filed May 26, 1896. Renewed March 11, 1898. Serial No. 673,541. (No model.)

To all whom it may concern:

Be it known that I, FRANK VITTNER, a resident of Chicago, in the county of Cook and State of Illinois, have invented certain new and useful Improvements in Windows; and I do hereby declare the following to be a full, clear, and exact description of the invention, such as will enable others skilled in the art to which it pertains to make and use the same.

10 The invention relates to windows, and has for its object to adapt them to be opened by swinging the sash laterally as well as by raising or lowering the same, and to provide for easily removing the sash from the casing; and the invention consists in the construction hereinafter described and particularly pointed out.

In the accompanying drawings, Figure 1 is a front view of my window, the upper and lower sashes being adapted to be moved down and up, respectively, in the usual manner, each sash being closed and in its normal situation. Fig. 2 is a section on line 2 2 of Fig. 1, but with the movable leaves of a hinge swung into position and engaged by pins on the lower sash. Fig. 3 is a front view of the hinge in the same position as in Fig. 1, but on a larger scale. Fig. 4 shows the same hinge with both leaves in the same plane. Fig. 5 is a side view, on a larger scale than in Fig. 1, of one of the hooks for securing a separable side sash-bar either to the sash or to the window-frame and showing a hook-case with parts broken away. Fig. 6 is a similar view showing the case in place on the separable side sash-bar and seated in the window-frame, the pivoted hook being in a position the reverse of that illustrated in Fig. 5. Figs. 7 and 8 are side views of different forms of double hooks. Fig. 9 is an enlarged section on line 9 9 of Fig. 1. Fig. 10 is an elevation of a window, the lower sash being partly open and the situation of the fixed leaf of the hinge modified. Fig. 11 is a section on line 11 11 of Fig. 10, both sashes being closed and arranged side by side and slightly raised, as necessary to engage the pins with the hinges, as indicated. Fig. 12 is an enlarged section of the lower part of the window, the sash being disposed as represented in Fig. 11. Fig. 13 is a section on line 13 13 of Fig. 12. Fig.

14 comprises a plan and elevation of a pin-supporting plate. Fig. 15 is a partial horizontal section of a modification.

55

Numeral 1 denotes a window-casing. 2 indicates the upper sash, and 3 the lower. 4 denotes detachable parts or sections of the sash sides. These are connected to the fixed portions of the sash sides by scarf-joints, (shown at 5,) and are normally held in fixed relation thereto by the arms of double or two-armed hooks 6, which engage pins 7, fixed in the sash side, the hooks being so formed as to engage the pins securely. The sash side being sectional, as described, its sections can be separated in horizontal lines transverse to the joint 5, and so that the separable section 4 may remain connected to the window-frame, while the sash, with its fixed side section, is swung open. The sash-weights are connected to the parts 4 of the sash sides by suitable cords (indicated by dotted lines at 20) and tend to hold the hooks engaged with the pins.

75

8 indicates cord-grooves. The outer arm of each of the double hooks 6 may when desired be made to engage a pin 9 on the window-casing to hold the separable pieces 4 of the sash sides in the window-casing when the sash is turned on its hinges to swing it open. The form of the double hook may be varied, as indicated in Figs. 7 and 8.

10 denotes hinges, one leaf 10' of each of which is fixed in the window-casing, while the other is normally free. The swinging leaf of each hinge has an open slot 11 in its upper end, and this leaf can be turned parallel with the front face of the sash side in position to receive a pin 7, fixed in the sash, when the latter has been slightly raised to carry the pins above the level of the leaf and then lowered to drop the pins into said slot 11. The sash being thus hinged and raised above the sill can be opened, the button-hooks having been suitably moved to allow the sash to separate freely from the side pieces 4 at the scarfed joint.

95

Each hook 6 is preferably inclosed in a casing or box 12, suitably slotted to permit the ends of its arms, which extend outside the case, to move freely.

The sash-hook boxes or cases 12 are let into

the separable piece 4 at 13, so that the outer surface of the box is in the same plane as that of the outer surface of the sashes. The pins 7 may be fixed in shallow recesses 14 in the sash, and need not extend outside its surface to interfere with moving either sash up or down to any desired extent.

The device would with care operate if the pins were without heads, as shown in Fig. 1 and elsewhere, as the weight of the sash will tend to prevent it from being pushed off from the pins; but for entire safety headed pins, such as indicated in Figs. 11 to 15, are preferred.

15 In Figs. 12 and 13 is shown one of two hinges for the lower sash, having its fixed leaf or part composed of an angle-iron 18, one side of which is screwed to the stile of the casing and the other to the front strip 19. The movable part or swinging leaf of the hinge is shown as engaged with a headed pin 7", fixed in a plate 21, let into and attached to the side rail of the sash. 22 denotes a parting-strip, to which and to the adjacent stile of the casing are secured similar hinges for the upper sash, the construction being like that just above described. Each sash has two hinges, the upper and lower hinges being preferably on the same level. The lower sash can be 20 slightly raised, as before stated, and its pins dropped into the slots of the swinging leaves of the hinges and then opened. The sash 2 can be lowered to the level of sash 3, as indicated in Figs. 11 to 13, and opened in like 25 manner, said lower sash having been first opened by turning on its hinges or by entire removal. If desired, the sash 3 can be moved entirely above sash 2 when lowered to the sill. For this purpose a slot 23 may be provided 30 in the casing.

Various details may be varied without departing from the invention, provided the essential principles of construction and operation are preserved. It is, however, practicable 45 and preferable to attach the hinges to the inner face of the stile without cutting entirely through it, as shown in Figs. 9, 12, and 13. These and like changes are considered to be within the scope of the invention. For further 50 example, the upper sash may be hinged at or near its normal level, as indicated in Figs. 1 and 9, an opening through the stile into the cord-channel being provided for the movable leaf of the hinge. It is not in this form necessary, however, to cut entirely through the 55 stile, it being only necessary to provide a pocket to receive the swinging leaf of the

hinge when the latter is inoperative, as indicated at 16 in Fig. 9.

One modification contemplated is indicated 60 in Fig. 15, in which 25 denotes a separable part of a sash side detachably connected to the stile by a hook 25', adapted to engage a pin 26 in the stile and provided with a thumb pin or bolt 27, which serves as a pivot for the 65 hook, the stile and separable part of the sash being suitably slotted to receive the hook, operating as stated. 28 denotes a hinge of common form. The sash can be swung open about the pintle of these hinges, the opposite 70 side sash having been freed from the retaining-strip or the strip removed.

Having described my invention, what I claim is—

1. In a window the combination of the casing, a sash having a side made of a fixed and a separable section, said casing and fixed sash side section having each a pin, and a hook pivotally supported in the separable section and adapted to fix the separable section either 80 to the sash side or to the casing by means of said pins, the two sash-sections being horizontally separable, substantially as described.

2. In a window the combination of the casing, a sash having a side made of a fixed and 85 a separable section, said casing and fixed sash side section having each a pin, a hook pivotally supported in the separable section and adapted to fix the separable section either to the sash side or to the casing by means of 90 said pins, the two sash-sections being horizontally separable, and a hinge on the opposite sash side, substantially as described.

3. In a window the combination of the casing, a sash having a side made of a fixed and 95 a separable section, said casing and fixed sash side section having each a pin, a hook pivotally supported in the separable section and adapted to fix the separable section either to the sash side or to the casing by means of 100 said pins, the two sash-sections being horizontally separable, and sash-weights connected to the detachable section and adapted to hold the hooks engaged with the pin either on the fixed sash-section or on the casing, 105 substantially as described.

In testimony whereof I have signed this specification in the presence of two subscribing witnesses.

FRANK VITTNER.
